(57) **CLAIM**

I claim the ornamental design for a comb with interchangeable name plate, as shown and described.

DESCRIPTION

FIG. 1 is a front elevational view of a comb with interchangeable name plate;

FIG. 2 is a front elevational view of the embodiment shown in FIG. 1;

FIG. 3 is a back elevational view of the embodiment shown in FIG. 1;

FIG. 4 is a top plan view of the embodiment shown in FIG. 1;

FIG. 5 is a bottom plan view of the embodiment shown in FIG. 1;

FIG. 6 is a left side elevational view of the embodiment shown in FIG. 1;

FIG. 7 is a right side elevational view of the embodiment shown in FIG. 1;

FIG. 8 is a cross sectional view taken along line 8—8 of the embodiment shown in FIG. 2; and,

FIG. 9 is a cross sectional view taken along line 9—9 of the embodiment shown in FIG. 2.
